UNITED STATES PATENT OFFICE.

JOSEPH A. SODEN, OF TOLEDO, OHIO.

SPARK-PLUG.

1,178,424.

Specification of Letters Patent.

Patented Apr. 4, 1916.

Application filed June 23, 1915. Serial No. 35,897.

To all whom it may concern:

Be it known that I, JOSEPH A. SODEN, a citizen of the United States, residing at Toledo, in the county of Lucas and State of Ohio, have invented new and useful Improvements in Spark-Plugs, of which the following is a specification.

This invention relates to certain novel and useful improvements in spark plugs for hydro-carbon engines and has particular application to the core or holder for the power electrode.

In carrying out the present invention it is my purpose to provide a spark plug 15 wherein the power electrode will be securely and effectively held in position in the core or electrode holder so that accidental displacement of the power electrode from the core, in the operation of the engine, will be eliminated.

It is also my purpose to provide a spark plug wherein the power electrode will be independent of the binding post and wherein the binding post may be readily removed 25 from the spark plug without disturbing the connection between the plug and the power electrode.

With the above recited objects in view and others of a like nature the invention 30 consists in the construction, combination and arrangement of parts hereinafter set forth in and falling within the scope of the claim.

In the accompanying drawing:—Figure 1 35 is a view in side elevation of a spark plug constructed in accordance with the present invention. Fig. 2 is a longitudinal sectional view through the spark plug. Fig. 3 is a transverse sectional view there- 40 through.

Referring now to the drawing in detail 1 designates a metallic shell circular in cross section and having one end screw-threaded to engage in the opening in the wall in the 45 cylinder of the engine, while 2 indicates a core or electrode holder disposed within the body 1, and suitably secured therein and formed of porcelain or other appropriate insulating material. The ground electrode is 50 secured to the cylinder end of the shell 1, as usual, while formed in the core 2 is an axial bore 3 and the outer end of the bore 3 is circumferentially enlarged as at 4. The side wall of the circumferentially enlarged 55 portion 4 of the bore tapers toward the outer end of the core and increases in di-

ameter toward such end of the core. Disposed within the bore 3 in the core 2 is a power electrode 5 having one end thereof spaced apart from the ground electrode on 60 the shell 1 to form the spark gap of the plug and the opposite end projecting beyond the outer end of the core 2.

6 designates a gasket composed of copper and asbestos. This gasket is disposed within the circumferentially enlarged portion 4 of the bore 3 and surrounds the portion of the electrode 5 within such enlarged part of the bore and is adapted to be driven downwardly within the enlarged portion of 70 the bore so as to bind against the tapering side wall of such enlarged portion thereby forming a secure connection between the electrode and the core so that accidental movement of the electrode 5 within the bore 75 3 will be eliminated. After the gasket 6 is driven home, a filler 7 of cement or analogous material is poured into the outer end of the circumferentially enlarged portion 4 of the bore and such filler acts to hold the 80 gasket in proper position in the bore.

In the present instance, the side wall of the core 2 adjacent to the outer end thereof is undercut to form a shoulder 8 and disposed upon the outer end of the core 2 is a 85 cup-shaped cap bearing 9 having the edge of the side wall thereof bent inwardly to engage the shoulder 8 and hold the cap to the core. Formed integral with the end wall 90 of the cap 9 and projecting outwardly therefrom coaxial with the bore 3 in the core 2 is a binding post 10. This binding post 10 is preferably hollow and the inner end portion thereof surrounds the adjacent end of the electrode 5 and is in contact therewith 95 so as to form an electrical connection between the binding post and the power electrode. This binding post 10 is adapted to receive the terminal of the current carrying wire and is equipped with a nut or the like 100 to insure a positive connection between the current carrying conductor and the binding post.

In the present instance, the outer end of the bore of the shell 1 is circumferentially 105 enlarged as at 11 and formed at the junction of the circumferentially enlarged portion 11 with the inner end portion of the bore is a shoulder 12. The portion of the electrode holder 2 within the circumferentially enlarged portion 11 of the bore of the shell is circumferentially enlarged at 13,

while the extremity of the electrode holder 2 projecting into the lower portion of the bore in the shell 1 tapers outwardly as at 14 and at the juncture of the enlarged portion 13 with the tapering portion 14 a shoulder 15 is formed.

Encircling the base of the tapering portion 14 and seated against the shoulder 15 is a gasket 16, while surrounding the circumferentially enlarged portion 13 of the electrode holder is a jacket 17 constructed of some suitable metal and having the lower end thereof flanged inwardly as at 18 and engaging the gasket 16 to hold the latter 15 against the shoulder 15. The remaining edge of the jacket 17 is pressed over the shoulder formed at the juncture of the outer end portion of the electrode holder with the circumferentially enlarged portion 13 so 20 that the jacket may be held in proper position upon the electrode holder. The flange 18 on the jacket 17 rests upon the shoulder 12 with the electrode holder disposed within the shell 1; and in order to hold the electrode holder securely within the shell a gland 19 is disposed about the electrode holder 2 and threaded into the circumferentially enlarged portion 11 of the shell and the inner end of the gland 19 engages the shoulder formed at the juncture of the circumferentially enlarged portion 13 of the electrode holder with the outer end portion of such shoulder and so coöperates with the shoulder 12 to secure the electrode holder in the shell.

It will be seen that I have provided a spark plug wherein the power electrode is securely and effectively held in the core.

while the outer end of such electrode is detachably associated with the binding post 40 thereby enabling the binding post to be removed from the core when it is desired without disturbing the connection between the electrode and the core.

I claim:—

In a spark plug, a shell having one end portion adapted to enter the opening in the cylinder and the bore at the other end portion circumferentially enlarged to form a shoulder, an electrode holder having one end portion disposed within said shell and circumferentially enlarged to correspond to the circumferentially enlarged portion of the shell, the inner end of said electrode holder on said circumferentially enlarged portion 50 tapering downwardly and forming a shoulder, a gasket seated upon the last-mentioned shoulder, a jacket surrounding the circumferentially enlarged portion of said electrode holder and having the lower end 60 thereof flanged inwardly and engaging said gasket and seated upon the shoulder formed in said shell, a gland threaded into the outer end of the circumferentially enlarged portion of said shell and bearing against the 65 enlarged portion of said electrode holder to secure the latter within the shell, a power electrode carried by said electrode holder, and a ground electrode connected to the inner end of said shell.

In testimony whereof I affix my signature in presence of two witnesses.

JOSEPH A. SODEN.
